Robert L. Sunderlin, Cincinnati, Ohio, assignor
to The Dyment Company, Cleveland, Ohio, a
corporation of Ohio

Application February 6, 1952, Serial No. 18,403

Term of patent 14 years

(Cl. D80—1)

To all whom it may concern:

Be it known that I, Robert L. Sunderlin, a citizen of the United States, residing at Cincinnati, county of Hamilton, and State of Ohio, have invented a new, original, and ornamental Design for a Display Device, of which the following is a specification, reference being had to the accompanying drawing, forming a part thereof.

Fig. 1 is a front elevation of a display device showing my new design;

Fig. 2 is a rear elevation of the same; and
Fig. 3 is a side elevation of the same.

The broken lines are shown for illustration purposes only.

I claim:

The ornamental design for a display device, as shown and described.

ROBERT L. SUNDERLIN.
